UNITED STATES PATENT OFFICE.

REUEL L. HUFFMAN, OF BROOKFIELD, MISSOURI.

BUTTON.

Application filed August 8, 1922. Serial No. 580,467.

To all whom it may concern:

Be it known that I, REUEL L. HUFFMAN, a citizen of the United States, and a resident of Brookfield, in the county of Linn and State of Missouri, have invented a new and Improved Button, of which the following is a full, clear, and exact description.

This invention relates to improvements in buttons primarily designed for attaching to garments.

The general object of the invention is the provision of a button of simple construction provided with means for positively attaching to any fabric.

15 A further object is the provision of a button provided with a neck which serves to retain the button body spaced from the fabric so that another fabric may be easily attached to the fabric.

20 This object is accomplished by providing a button body having a tubular neck depending therefrom, said neck having mounted on its inner wall hook-engaging means with which the resilient hooks of an attaching plate engage.

25 These and other objects of the invention will be more clearly understood from the following detailed description and accompanying drawings.

30 Figure 1 is a vertical section through the button showing it attached to a fabric.

Fig. 2 is a bottom plan view of the button body.

Fig. 3 is a top plan view of the attaching plate.

35 In carrying out my invention in accordance with the illustrated example a disc-shaped body 10 having its upper face slightly curved is provided. Depending from the body 10 is a tubular neck 11. Around the inner wall of this tubular neck an annular flange 12 extends. The portion of the body 10 located above the tubular neck has a curved recess 13 formed therein, thus providing an arched roof for the tubular neck.

An attaching plate consisting of a hollow

body 14 having a circular opening in its upper wall and three resilient hook members 15 extending upward, is provided. The hook members are positioned about the circular opening in the upper wall of the body 14. A circle described to touch the outer faces of the shanks of the hooks should have a diameter approximately the same as the internal diameter of the annular flange 12. The projections 16 of the hooks 15 face outward.

In attaching this button to a fabric 17, the hooks 15 are first forced through the fabric. The body of the button is then positioned on the hooks with the flange 12 resting on the curved faces 18 of the projections 16. The body 10 is then forced downward and the flange 12 passes over the projections which seat on its upper face and the button positively attached to the fabric.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claim.

Claim.

A button comprising a body, a cylindrical neck extending from one side of the body and coaxial therewith, an annular flange extending inwardly around the outer end of the cylindrical neck and an attaching plate 80 having a plurality of resilient hooks extending parallel to the axes of the body and attaching plate in assembly, said hooks having shanks arranged so that the outer lateral faces of the shanks engage the inner peripheral face of the flange in assembly, said hooks also having outwardly extending projections at their free ends adapted to extend over and positively and directly engage the inner lateral face of the flange in the 85 assembly.

REUEL L. HUFFMAN.
